HYDRAULIC FEED MECHANISM

Ralph E. Price, Highfield, Md., assignor to Landis
Tool Company, Waynesboro, Pa.

Application August 26, 1948, Serial No. 46,280

17 Claims. (Cl. 51—103)

1

This invention relates to feed mechanisms for grinding machines, particularly centerless grinders.

The primary object of this invention is to provide an automatic feed cycle. By this is meant a cycle which will be repeated as often as desired without attention from the operator.

A further object is to provide a control mechanism which will function to initiate the cycle as well as cause a dwell at each end of the feed movement.

A further object is to provide a work ejecting mechanism operable in connection with said feed mechanism.

Figure 1 is perspective showing the structure of the feed mechanism.

Figure 2 shows a hydraulic diagram for a feed mechanism and a work ejecting mechanism for a centerless grinder.

Numerical 10 indicates a grinding wheel base slidably mounted on a bed 11 for movement toward or from operative position. A grinding wheel 12 is rotatably mounted in said base. Said movement may be effected manually or by power.

The manual feeding means consists of a hand wheel 15 for driving through suitable gearing to a worm gear 16 on an axially slidabie shaft 17. Said worm gear engages a worm wheel 18 on feedscrew shaft 19. All this mechanism is carried in wheel base 10.

The feedscrew 19 is in operative engagement with a nut 20 in bed 11.

Rotation of hand wheel 15 causes rotation of worm 16, worm wheel 18, and feedscrew 19 in nut 20, thus causing feedscrew to move relative to the nut and carrying the wheel base 10 with it.

The power means for moving said wheel base consists of a piston 25 at the opposite end of shaft 17 from hand wheel 15. Said piston is slidably mounted in a cylinder 26. The stroke of said piston and hence the feed movement of the wheel support 10 may be adjusted by means of adjustable stop 27.

Fluid under pressure may be introduced alternately to opposite ends of said cylinder as will be described more in detail later.

Movement of piston 25 in response to the introduction of fluid under pressure into cylinder 26 results in an endwise movement of shaft 17 and worm 16. Under these circumstances, worm 16 acts as a rack and thus causes rotation of worm wheel 18 and, hence, feedscrew 19.

While the feed mechanism disclosed herein is applicable to grinding machines of many types, I prefer to illustrate it as applied to a centerless grinder. Accordingly, the diagram Figure 2 in-

2

cludes a control wheel 30 peripherally opposed to grinding wheel 12. The method of driving the grinding wheel at the conventional speed and the control wheel at a much slower speed is well known and need not be shown here.

A work piece 35 is supported between the peripheral surfaces of the grinding and control wheels on a work rest 36.

Fluid under pressure is directed alternately through lines 40 and 41 to opposite ends of cylinder 26 to move grinding wheel 12 toward and from operative position. Said fluid under pressure is supplied by a pump 50 through line 51 to a reversing pilot valve 52. Valve 52 directs fluid alternately to opposite ends of a cycle control valve 60 and a reversing valve 70.

Valve 52 is connected through rod 53 to one end of a lever 54. Said lever is pivoted at an intermediate point 55. The other end is in the form of a yoke having spaced opposing adjusting screws 56 and 57. Between said screws is a dog member 80 attached to timer piston 81. Each end of said valve has an axial bore 82_R and 82_L and an intersecting radial bore 83_R and 83_L, the function of which will be discussed later.

Pilot valve 52 receives fluid under pressure from pump 50 through line 51 and directs it alternately through lines 71 and 72 to opposite end of reversing valve 70. It also directs said fluid alternately through lines 61 and 62 to opposite ends of valve 60.

Reversing valve 70 receives fluid from pump 50 through line 51 and in the position shown is directing said fluid through line 40 to the head end of cylinder 26. Exhaust fluid from the opposite end of cylinder 26 passes through line 41 to valve 70 which directs it to one of the exhaust ports of said valve. When valve 70 is shifted to the left, fluid from line 51 passes through line 41 to the right end of cylinder 26 and shifts piston 25 to the left. Exhaust fluid from the left end of the cylinder may pass freely through line 28, check valve 29, lines 40 and 42 to valve 70 and the left end exhaust passage of said valve. This permits a rapid movement of wheel base 10 to place grinding wheel 12 in grinding position.

When piston 25 closes off line 28, the only outlet is through line 40 and throttle valve 43 to valve 70 and the left-hand exhaust port. Throttle valve 43 may be set to provide a suitable grinding feed.

Valve 60

While valve 70 directs fluid under pressure to actuate feed piston 25 to the right for backing off wheel 12, valve 60 in the right-hand position

shown directs fluid under pressure through line 63 to shift timing piston 81 in cylinder 84 to the right. Said valve receives its supply of fluid from line 51 through line 58. A selector valve 59 in line 58 serves to render valve 60 inoperative so far as the actuation of timing piston 81 is concerned. In one position the fluid under pressure is supplied to valve 60, and in the other position of valve 59 the portion of line 58 between valve 60 and valve 59 is connected with exhaust through valve 59. In this position of valve 59, reversing pilot valve 52 must be actuated manually.

Said piston 81 has a dog member 80 operable between screws 56 and 57 in reversing lever 54. As piston 81 moves to the right, exhaust fluid first passes through line 65 to valve 60 and the left exhaust port therein. As said piston closes line 65, exhaust fluid must by-pass through throttle valve 66, which is set to delay the actuation of reversing lever 54 for an interval suitable for loading a work piece into the machine. Piston 81 has axial passages at each end indicated as 82_R and 82_L respectively. Said passages connect with radial passages indicated as 83_R and 83_L respectively.

The period during which movement of piston 81 is controlled by valve 66 provides time for backing off grinding wheel 12, removing a finished work piece and placing an unground work piece in the machine. As soon as passage 83_R comes into line with line 65, exhaust fluid from the right-hand end of cylinder 84 may pass freely through line 65 and valve 60 to the left end exhaust port. Piston 81 then moves quickly to the end of its stroke and dog 80 engages screw 57 to shift lever 54 and valve 52 to the left. For a continuous cycle, screw 57 is adjusted so that dog 80 engages it just after passage 83_R comes into line with line 65. If it is desired to have the wheel base 10 stop in the inoperative position, screw 57 may be backed off so that dog 80 does not engage it at the end of the movement of piston 81. When screw 57 is adjusted in this manner, the wheel base 10 will reverse automatically at the end of the grinding operation; but it will stop in the back position and remain there until the operator shifts lever 54 to the left.

Assume that valve 59 and screw 57 are adjusted for a complete automatic cycle. When pilot valve 52 is shifted to the left, valves 60 and 70 are also shifted to the left. Valve 70 directs fluid through line 41 to the right-hand end of cylinder 26 and piston 25 moves to the left, turning feed-screw 19 at a rapid rate until piston 25 cuts off line 28 through which exhaust fluid may pass freely to check valve 29, line 42, line 40 and the left end exhaust line from valve 70. Thereafter, exhaust fluid from the left end of cylinder 26 is passed through line 40 and throttle valve 43 which determines the rate of movement of piston 25 during the grinding operation. From valve 43 fluid passes through another portion of line 40 to valve 70 which directs it to the left exhaust port of said valve.

Exhaust fluid in line 40 also acts on the left end of valve 90 to shift it to the right against spring 91. Check valve 29 is held in closed position by a spring, not shown, slightly heavier than spring 91 so as to assure sufficient pressure to actuate valve 90. Valve 90 is held in this position by exhaust pressure during the entire feeding stroke. At the end of the feeding stroke, piston 25 comes to rest against adjustable stop 27. In the absence of movement of piston 25, exhaust pressure in line 40 disappears and spring 91 returns valve 90 to the left-hand position.

In the left-hand position of valve 60 fluid under pressure from line 58 is directed through line 100 to valve 90. So long as valve 90 is in the right-hand position, the fluid in line 100 can move no further. At the end of the feeding stroke, valve 90 returns to the left-hand position, connects line 100 with line 101 leading to the right-hand end of timing cylinder 84 and starting the timing movement of piston 81. Thus, the timing period begins not with the movement of piston 25, but after the piston reaches the end of its stroke and the feeding movement of the grinding wheel is stopped. Timing piston 81, therefore, times only the spark out period. The duration of this period is determined by throttle valve 102 through which exhaust fluid from the left end of cylinder 84 and line 63 must pass to reach line 64, which is connected through valve 60 with the left end exhaust port of said valve. A description of the quick initial and final movements of piston 81 has been omitted here, since it is identical with that described in connection with the movement of this piston in the opposite direction.

25

Work ejector

The ejecting mechanism is shown for the purpose of illustration as a cylinder 110 having slidably mounted therein a piston 111. A piston rod 112 on said piston extends from the cylinder into the space between the grinding wheel 12 and control wheel 39. Said piston may be actuated by fluid under pressure at the left end of said cylinder to move said piston and piston rod to the right against the action of spring 113. When so moved, rod 112 pushes work piece 35 out of the grinding throat. Piston 111 is actuated in timed relation with the movement of wheel base 10 toward and from operative position. This timed relation is effected by hydraulic connection between cylinder 26 and a pair of valves 115 and 116. These valves are shifted from one position to another hydraulically. However, they control a supply of air under pressure for the operation of piston 111. The supply of air under pressure enters valve 115 through line 125 from which it is directed through line 126 to valve 116. Valve 116 connects line 126 with line 127 leading to cylinder 110. The only time air from line 125 can reach cylinder 110 is with valve 115 in the right-hand position as shown and valve 116 in the left-hand position or opposite to that shown.

During the feeding stroke of piston 25, fluid under pressure is directed from valve 70, line 41 to the right end of cylinder 26. The fluid under pressure from line 41 also passes through line 120 to the right end of valve 115 and through throttle valve 121 to the right end of valve 116. Valve 115 is shifted to the left position immediately and cuts off the supply of air from line 125 through line 128 to valve 116. The movement of valve 116 is delayed due to the setting of throttle valve 121, so that the air is sure to be shut off before said valve reaches the left-hand position in which it connects the air supply of line 126 with line 127, leading to ejector cylinder 110. It is necessary to delay the action of valve 116 so that it does not move simultaneously with valve 115, or even ahead of it, and thus connect said ejector cylinder with the air supply before it has been cut off by valve 115. Thus, out of time operation of the ejector is prevented.

After a work piece has been ground and piston 25 moves from left to right to withdraw the grinding wheel from grinding position, said piston

uncovers line 130 leading to the left-hand end of valves 115 and 116. Valve 115 moves immediately to the right and connects air line 125 with line 126. Valve 116 moves more slowly than valve 115 because of throttle valve 121 through which the exhaust fluid from valve 116 must pass. Thus, before valve 116 has an opportunity to break the connection between line 126 and 127, ejector piston 111 and rod 112 have been moved to the right and work piece 35 is ejected. Piston 111 is held in the right-hand position until valve 116 reaches its right-hand position, connecting line 127 with exhaust port 128. Spring 113 then shifts piston 111 and rod 112 to the left in which position rod 112 serves as a locating means for the next work piece.

I claim:

1. In a machine tool, a hydraulic system including a motor for shifting a machine element, a supply of fluid under pressure for actuating said motor, a reversing mechanism for determining the direction of movement of said motor, including a pilot valve and a reversing valve, an actuating mechanism for determining the interval during which said motor remains stationary at either end of its movement, including a motor for actuating the pilot valve and a reversing valve also actuated by said pilot valve for directing fluid under pressure alternately to opposite ends of said pilot valve operating motor.

2. In a machine tool, a hydraulic system including a motor for shifting a machine element, a supply of fluid under pressure for actuating said motor, a reversing mechanism for determining the direction of movement of said motor, including a pilot valve and a reversing valve, an actuating mechanism for determining the interval during which said motor remains stationary at either end of its movement, including a motor for actuating the pilot valve and a second reversing valve also actuated by said pilot valve for directing fluid under pressure alternately to opposite ends of said pilot valve operating motor, and means for cutting off the supply of fluid to said second reversing valve whereby to prevent operation of said timing mechanism.

3. In a hydraulic system, a motor for shifting a machine element, a supply of fluid under pressure for actuating said motor, a reversing mechanism for determining direction of movement of said motor, a timing mechanism for determining the interval during which the motor is stationary at either end of its movement, a timing valve operated by said reversing mechanism for actuating said timing mechanism and a valve between said timing valve and one end of said timing mechanism operable at the end of said motor movement in one direction for initiating operation of said timing mechanism.

4. In a machine tool, a hydraulic system including a motor for shifting a machine element, a supply of fluid under pressure for actuating said motor, a reversing mechanism for determining the direction of movement of said motor, a timing mechanism for determining the interval during which said motor remains stationary at either end of its movement, a timing valve for directing fluid to actuate said timing mechanism, and a pressure operated valve between said timing valve and said timing mechanism for preventing operation of said timing mechanism until said motor has moved to a predetermined position.

5. In a machine tool, a hydraulic system, a motor for shifting a machine element, a supply

of fluid under pressure for actuating said motor, a reversing mechanism for determining the direction of movement of said motor, a timing mechanism for determining the interval during which said motor remains stationary at either end of its movement, a timing valve for directing fluid to actuate said timing mechanism, and a pressure operated valve between said timing valve and said timing mechanism and responsive to movement of said motor for determining the starting time of said timing mechanism.

6. In a machine tool, a hydraulic system including a motor for shifting a machine element, a supply of fluid under pressure for actuating said motor, a reversing mechanism for determining the direction of movement of said motor, including a pilot valve and a reversing valve, an actuating mechanism for determining the interval during which said motor remains stationary at either end of its movement, including a motor for actuating the pilot valve and a reversing valve also actuated by said pilot valve for directing fluid under pressure alternately through opposite ends of said pilot valve operating motor, and a valve actuated by exhaust fluid from said first motor during the feeding movement for preventing operation of said pilot valve actuating motor until the end of said feeding movement.

7. In a hydraulic system, a motor for shifting a machine element, a supply of fluid under pressure for actuating said motor, a reversing mechanism for determining direction of movement of said motor, a timing mechanism for determining the interval during which the motor is stationary at either end of its movement, a timing valve operated by said reversing mechanism for actuating said timing mechanism, a spring loaded cutoff valve between said timing valve and timing mechanism which is operated by back pressure of exhaust fluid from said motor in one direction of its movement to prevent actuation of the timing mechanism until said motor reaches the end of its stroke in one direction.

8. In a machine tool, a base, a support slidably mounted on said base for a movement toward and from operative position relative to a work piece, a cutting tool on said support, power means for effecting said movement including a piston and cylinder, a supply of fluid under pressure therefor, a work ejecting mechanism, and connections between said cylinder and said work ejecting mechanism for actuating said mechanism, including a pair of valves, one of which is shifted instantly to direct fluid to the second valve, said second valve directing said fluid to said ejector and then moving to position to connect said ejector with exhaust.

9. In a machine tool, a base, a support slidably mounted on said base for a movement toward and from operative position relative to a work piece, a cutting tool on said support, power means for effecting said movement including a piston and cylinder, a supply of fluid under pressure therefor, a work ejecting mechanism and connections between said cylinder and said work ejecting mechanism for actuating said mechanism including a separate source of fluid under pressure for actuating said ejector, a valve for controlling the flow of said fluid to said ejector and means for actuating said valve after said tool has started to move from operative position.

10. In a machine tool, a base, a support slidably mounted on said base for a movement toward and from operative position relative to a work piece, a cutting tool on said support, power means for

effecting said movement including a piston and cylinder, a supply of fluid under pressure therefor, a work ejecting mechanism and connections between said cylinder and said work ejecting mechanism for actuating said mechanism including a separate source of fluid under pressure for actuating said ejector, a valve for controlling the flow of said fluid to said ejector and a conduit for conducting fluid under pressure from said cylinder to actuate said ejector valve.

11. A grinding machine including peripherally opposed grinding and control wheels, a work rest for rotatably supporting a work piece in operative relation to said wheels, a work positioning and ejecting mechanism for locating a work piece in and ejecting it from said operative relation with said wheels, including a piston and a cylinder therefor, means for effecting a feeding movement of one of said wheels toward the other, including a second piston and cylinder and a conduit from a point in said feed cylinder intermediate the ends thereof for conducting fluid under pressure to effect operation of said ejector piston after a predetermined movement of said feed piston.

12. In a machine tool, a base, a support slidably mounted on said base for a movement toward and from operative position relative to a work piece, a cutting tool on said support, power means for effecting said movement including a piston and cylinder, a supply of fluid under pressure therefor, a work ejecting mechanism, and connections between said cylinder and said work ejecting mechanism for actuating said mechanism, including a pressure-operated valve operable at a controlled rate in one direction and having spaced ports for first directing fluid under pressure to actuate said ejector and thereafter directing said fluid to reset said ejector.

13. In a machine tool, a base, a support slidably mounted on said base for a movement toward and from operative position relative to a work piece, a cutting tool on said support, power means for effecting said movement including a piston and cylinder, a supply of fluid under pressure therefor, a work ejecting mechanism, and connections between said cylinder and said work ejecting mechanism for actuating said mechanism, including a valve operable at a controlled rate for first directing fluid under pressure to actuate said ejector and thereafter directing fluid to reset said ejector, and a second pressure operated valve for controlling the supply of fluid to said ejector valve.

14. In a machine tool, a base, a support slidably mounted on said base for a movement toward and from operative position relative to a work piece, a cutting tool on said support, power means for effecting said movement including a piston and cylinder, a supply of fluid under pressure therefor, a work ejecting mechanism including a piston and cylinder and an ejector actuated by said piston, resilient means for urging said piston in one direction, a pressure-operated valve oper-

able at a controlled rate and having spaced ports for first directing fluid to actuate said ejector piston and thereafter permitting the discharge of fluid from said ejector cylinder independently of the movement of said first-mentioned piston.

15. In a machine tool, a base, a support slidably mounted on said base for a movement toward and from operative position relative to a work piece, a cutting tool on said support, power means for effecting said movement including a piston and cylinder, a supply of fluid under pressure therefor, a work ejecting mechanism, and connections between said cylinder and said work ejecting mechanism for actuating said mechanism, including a valve operable after said piston moves said tool toward inoperative position for directing fluid under pressure to actuate said ejector and means for retarding the movement of said valve whereby fluid under pressure is first directed to said ejector cylinder and thereafter said ejector cylinder is connected to an exhaust line.

16. In a machine tool, a tool support, a feed mechanism for moving said support toward and from operative position, comprising a piston and cylinder, a supply of fluid under pressure for driving same, control means including a reversing valve, a timing mechanism comprising a free piston having a lost motion connection with said reversing valve, means actuated at the end of the movement of said feed piston toward operative position to initiate the operation of said timing piston, and means actuated by said timing piston after a predetermined interval for shifting said reversing valve to return said tool to inoperative position.

17. In a machine tool, a tool support, a feed mechanism for moving said support toward and from operative position comprising a piston and cylinder, a supply of fluid under pressure for driving same, control means including a reversing valve, a timing mechanism, means actuated in response to a drop in exhaust pressure at the end of the movement of said piston for shifting said tool into operative position to initiate the operation of said timing mechanism, and means actuated by said timing mechanism after a predetermined interval for shifting said reversing valve to return said tool to inoperative position.
